Attorney

UNITED STATES PATENT OFFICE.

PATRICK H. CARROLL, OF WHITE CREEK, NEW YORK, ASSIGNOR OF ONE-HALF TO
MARSHALL GARDNER, OF WHITE CREEK, NEW YORK.

CAN-WASHER.

1,172,430.

Specification of Letters Patent. Patented Feb. 22, 1916.

Application filed November 27, 1915. Serial No. 63,851.

To all whom it may concern:

Be it known that I, PATRICK H. CARROLL, a citizen of the United States, residing at White Creek, in the county of Washington 5 and State of New York, have invented certain new and useful Improvements in Can-Washers, of which the following is a specification, reference being had to the accompanying drawings.

10 This invention relates to certain improvements in can washers and it is an object of the invention to provide a device of this general character having novel and improved means whereby the interior of a can may be 15 readily and effectively cleansed.

Furthermore it is an object of the invention to provide a device of this general character wherein the brushes are capable of movement relatively to the supporting 20 member, and whereby said brushes are caused to move under the influence of the operating means for the brushes.

The invention consists in the details of construction and in the combination and arrangement of the several parts of my improved can washer whereby certain important advantages are attained and the device is rendered simpler, less expensive and otherwise more convenient and advantageous for 25 use, all as will be hereinafter more fully set forth.

The novel features of the invention will be carefully defined in the appended claims.

In order that my invention may be 30 better understood, I will now proceed to describe the same with reference to the accompanying drawings, wherein—

Figure 1 is a view partly in elevation and partly in section of a washer constructed in accordance with an embodiment of my invention. Fig. 2 is a sectional view taken substantially on the line 2—2 of Fig. 1, with the supporting stem in elevation; and Fig. 3 is a sectional view taken substantially on the 40 line 3—3 of Fig. 1.

As disclosed in the accompanying drawings, 1 denotes a supporting stem of predetermined dimensions and cylindrical in form and having rotatably engaged with its lower 45 extremity the ferrule 2 from which radiate the oppositely arranged perforate ears 3, in each of which is pivotally engaged the shank 4 of a brush B, said shank being preferably formed of wire of requisite gage. The lower extremity of the stem 1 is provided

with the annular flange 5 to retain the ferrule 2 upon the stem. Loosely mounted upon the stem 1 is a second ferrule 6 also provided with the oppositely disposed bifurcated ears 7 in the kerfs of which are pivotally engaged the upper extremities of the elongated members 8, preferably of wire, the opposite extremities of said members 8 being operatively engaged with the brushes B as indicated at 9. It will be perceived that upon moving the ferrule 6 upwardly of the stem 1 the brushes B will be adjusted into a folded position whereby the device may be readily inserted within the can to be washed.

At a predetermined point adjacent the upper extremity of the stem 1 is loosely mounted the sleeve 10, the downward movement of which is limited by the pin 11, disposed transversely through the stem 1 at a predetermined point thereon. The sleeve 10 adjacent its upper end is provided with the stub shaft 12 on which is rotatably mounted the gear 14 provided with the operating member 15, herein disclosed as a conventional crank. The gear 14 meshes with the gear 15 loosely mounted upon the sleeve 10, and maintained in mesh with the gear 14 through the medium of the annular outstanding flange 16. The gear 15 has disposed therethrough the rods 17 which extend downwardly and are operatively engaged with the ears 7 of the ferrule 6 and extending within the bifurcations of the ears 7. It will be observed that the pivots 18 serve as a medium to maintain both the rods 17 and the members 8 operatively engaged with said ears.

It will be perceived that in order to adjust the brushes B into folded position, the handle 15 may be engaged to impart upward movement to the sleeve 10, whereupon the ferrule 6 will also be moved upwardly and result in an upward movement being imparted to the brushes B also.

From the foregoing description, it is thought to be obvious that a can washer constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and

for this reason I do not wish to be understood as limiting myself to the precise arrangement and formation of the several parts herein shown in carrying out my invention in practice.

I claim:

1. A can washer comprising a stem, a ferrule rotatably mounted on the stem adjacent an extremity thereof, brush members pivotally engaged with the ferrule, a second ferrule slidably mounted upon the stem, elongated members pivotally engaged with the second ferrule and operatively engaged with the brush members, and means imparting rotation to the last named ferrule.
2. A can washer comprising a stem, a ferrule rotatably mounted on the stem adjacent an extremity thereof, brush members pivotally engaged with the ferrule, a second ferrule slidably mounted upon the stem, elongated members pivotally engaged with the second ferrule and operatively engaged with the brush members, a sleeve slidably mounted on the stem, a member rotatably

supported by the sleeve, rods connecting the member and the last named ferrule, and means for imparting rotation to the member.

3. A can washer comprising a stem, a ferrule rotatably mounted on the stem adjacent an extremity thereof, brush members pivotally engaged with the ferrule, a second ferrule slidably mounted upon the stem, elongated members pivotally engaged with the second ferrule and operatively engaged with the brush members, a sleeve slidably mounted on the stem, a member rotatably supported by the sleeve, rods connecting the member and the last named ferrule, a second member rotatably supported by the sleeve and in mesh with the first named member, said second named member being provided with means for rotating the same.

In testimony whereof I hereunto affix my signature in the presence of two witnesses.

PATRICK H. CARROLL.
